UNITED STATES PATENT OFFICE.

MARION M. ROBERTS, OF GOSSETT, ILLINOIS.

HINGE.

1,072,364.

Specification of Letters Patent.

Patented Sept. 2, 1913.

Application filed July 10, 1912. Serial No. 708,727.

To all whom it may concern:

Be it known that I, MARION M. ROBERTS, a citizen of the United States, resident of Gossett, in the county of White and State of Illinois, have made a certain new and useful Invention in Hinges; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a perspective view of the invention with the door open to about ninety degrees. Fig. 2 is a side view of the invention with the door closed. Fig. 3 is a side view of the invention with the door fully open. Fig. 4 is a plan view of the blank for one of the hinge members. Fig. 5 is a similar view of the blank for the other hinge member having the screw threads in dotted lines.

The invention relates to hinges designed to be used chiefly for doors, and it consists in the novel construction and combinations of parts, as hereinafter set forth.

The object of the invention is to provide improved right and left hinges which can be readily made of wrought or plate steel, and are of such character as to possess important functions with reference to the operation of the door.

In the accompanying drawings, illustrating the invention, the numeral 2 indicates the stationary leaf of the hinge, which is designed to be secured to the casing, and the movable leaf, which is to be secured to the door. Numerals 4 and 5 represent the blanks for these leaves, which are cut of plate steel. In these blanks, which are designed to interfit to avoid waste of material, the movable leaf blank is cut out at the lower edge to provide plate material for the lower knuckle offset of the other blank, which is cut out at its upper edge to provide plate material for the upper knuckle offset of the first blank, each blank being intermediately and angularly recessed to provide plate material for the intermediate angular knuckle offset of the other blank.

The stationary leaf 2 consists of a rectangular bearing plate 6 having a bottom offset knuckle 7, and above the same and

separated therefrom by an interval of sufficient extent to receive a knuckle of the movable leaf, a second knuckle 8, which is located below the upper margin of the plate sufficiently to allow for the reception of the upper knuckle of the movable leaf, so that the upper edges of the two plates will be substantially on the same level when the leaves are closed together.

The top or upper edge of the upper knuckle 8 is plane and horizontal, as is also the bottom of the lower knuckle 7. The top of this lower knuckle 7 is provided with a low incline 9, extending upward slightly from the edge of the plate to a salient angle 10, about one-third the circumference of the knuckle, beyond which a downward sharper incline 12 extends for another third of such circumference to a reentrant angle or low point 13, whence the knuckle edge extends slightly upward to the plate, its end being brought in juxtaposition with or engaging the initial portion of the bend of the knuckle, at a point below the commencement of the incline 9.

The bottom edge of the upper knuckle 8 of this plate extends outward from the plate, and substantially level, a short distance, to the commencement of a reversed downward incline 14, which is of similar slope but longer than the incline 12 of the lower knuckle, the point of its commencement being nearer the plate than the salient 10 or point of commencement of the incline of the lower knuckle. At the end of the incline 14 a vertical shoulder 15 extends upward a short distance to a horizontal portion 16, which ends at a second vertical shoulder 17, which terminates at a horizontal portion 18 of the edge, which extends to the plate. The reversed incline 14 of this hinge leaf is made longer than its incline 12 in order that it shall extend beyond the vertical line of the salient 10, and that the reversed incline shall be in bearing position when the lower incline 12 commences to act on the intermediate or lower knuckle of the movable leaf, and shall have a lap bearing when the hinge is closed.

The movable leaf is also provided with two knuckles, an upper knuckle 20 having a horizontal bottom and top, and a lower knuckle 21 having on its upper edge a long incline 22, and on its lower edge a parallel reversed incline 23, of less length.

The upper knuckle 20 of this leaf is threaded in its eye, to engage a threaded portion 24 of the hinge pindle 25, which is formed with a shouldered head 26 which is provided with a wrench seat. The pindle is in this way designed to be firmly secured to this knuckle and, while it engages the two knuckles of the other leaf and the intermediate knuckle of the movable leaf, it is prevented from being worked, by the up and down movements of the door, out of position.

The upper edge or top of the lower knuckle 21 of the movable leaf is usually formed with vertical shoulders 27 terminating horizontal portions of the edge. This edge is also provided as above stated with an extended incline 22, of equal angular degree to the long reversed incline 14 of the other leaf, so that these inclines work upon each other, and lap when the door is closed. The lower edge of this knuckle is provided with three reverse inclines, corresponding to the inclines of the upper edge of the lower knuckle of the stationary leaf; the first incline extending slightly downward from the leaf as at 29 for about one third of its circumference to a salient angle 31, whence the second and sharper reverse incline extends upward as at 23 to a reentrant angle, from which the third reverse incline 28 extends slightly downward to the body of the plate above the initial point of the knuckle edge. The bottom or reversed incline 23 has the same angular direction as the incline 22 of the upper edge of this knuckle, which extends beyond the vertical line of the salient 31, or nearer to the hinge plate.

When the hinge or door is closed, the meeting edges of the upper knuckles of the leaves fit together, as do the meeting edges of the lower knuckles. But the meeting edges of the intermediate knuckles are separated, except at the lap of the long inclines 14 and 22 hereinbefore referred to.

When the door is being opened, the moving leaf of the hinge rides upward, because of the engagement of the reversed incline of its lower knuckle with the upward incline of the knuckle of the stationary leaf, until the salient angle of the movable knuckle passes that of the stationary knuckle, after which the movable leaf and door fall slightly and gradually, because of the engagement of the flatter inclines in rear of these salient angles. In this manner it is designed to cause the door to assist the opening movement by its own gravity—the action continuing until the door is fully open.

When the door is being closed, and as the salient angles of the lower knuckles pass each other, the sharper closing inclines come into action, under the gravitation of the door, to bring it to closed position. At the same time the long bottom incline of the in-

termediate knuckle of the stationary leaf engages the long incline of the movable leaf, and is designed to force the door downward to close upon its sill and to keep it in that position, because of the lap of these inclines. This lap bearing also strengthens the knuckles when the hinge is closed, because of their mutual bracing effect.

The operation of these hinges is designed to cause the door to rise high enough in opening to clear rugs, carpets and mats, and when shut to secure a close or water-tight joint with the sill.

The movable plate may be of any angular form, that is to say, bent at right angles to the portion next the knuckles, in order to provide a more extended bearing to be applied to the face of the door instead of the rear edge. In this way the attachment surface or purchase on the door is made sufficient to secure the leaf or plate firmly against a tendency to become loosened because of the resistance of the inertia of the door in its up and down movements in opening and closing.

Having described the invention, what I claim and desire to secure by Letters Patent is:

1. A hinge comprising in its construction, a stationary leaf having the top of its lower knuckle provided with a middle sharp incline of about one-third its circumference rising toward the leaf, and on each side thereof flatter parallel inclines, and the bottom of its upper knuckle provided with a sharp incline of the same degree of slope as said middle sharp incline but lesser length, a movable leaf having between and engaging both knuckles of the stationary leaf a knuckle provided on its lower edge with a middle sharp incline rising from the leaf and lateral flatter parallel inclines corresponding to those of said lower knuckle, and on its upper edge with a sharp incline parallel to said middle incline and engaging the incline of the other leaf.

2. A hinge comprising in its construction, a stationary leaf having a lower knuckle provided on its upper edge with a middle upward incline rising from the leaf and joining a downward incline at a salient angle, and an upper knuckle provided on its lower edge with an upward incline rising from the leaf and extending beyond the apex of such salient angle, and a right-angled movable leaf having an intermediate knuckle provided on its lower edge with a middle upward incline rising from the leaf and joining a downward incline at a salient angle, and on its upper edge with an upward incline extending beyond the apex of the latter salient angle to provide a bracing and lapping engagement with the upward incline of the upper knuckle of the other leaf.

3. A pair of plate blanks for a hinge, com-

prising a leaf blank having its upper edge rectangularly cut out, and its middle portion angularly recessed between knuckles offsets having inclined angular edges marginal to said recess, and a corresponding leaf blank having an upper rectangular knuckle offset, a lower knuckle offset fitting the inclined angular edge of the lower knuckle offset of the first leaf blank and an

intermediate recess corresponding to the upper knuckle offset of said first leaf blank.

In testimony whereof I affix my signature, in presence of two witnesses.
